Primary Examiner — Mary Ann Calabrese*Assistant Examiner* — Mark David Wolfley(74) *Attorney, Agent, or Firm* — Bold IP PLLC; Houda El-Jarrah**(57) CLAIM**

The ornamental design for a clothing stretching device as shown and described.

DESCRIPTION

FIG. 1 is a front view of a clothing stretching device showing my new design, the back view being a mirror image thereof;

FIG. 2 is a left view thereof, the right view being a mirror image thereof;

FIG. 3 is a top view thereof; and,

FIG. 4 is a bottom view thereof.

The broken lines shown in the Figures depict portions of the article that form no part of the claimed design.

1 Claim, 3 Drawing Sheets(56)
